UNITED STATES PATENT OFFICE.

ELMER HAMMOND, OF BALTIMORE, MARYLAND, ASSIGNOR TO WESTERN MARYLAND RAILWAY COMPANY, OF BALTIMORE, MARYLAND, A BODY CORPORATE OF THE STATES OF MARYLAND AND PENNSYLVANIA.

FLOATING FLUID-LOADING RACK.

Application filed February 27, 1926. Serial No. 91,270.

This device relates to a loading apparatus made up of a series of metal pipes for delivery of fluids to carriers.

More particularly the object of the invention is to provide an efficient means of transfer of fluids from containers similar to those that may be found at manufacturing, shipping, storage or transfer points on land, docks, or floating structures, to receiving vehicles.

The apparatus is particularly adapted to loading such a fluid as gasoline from storage tanks on land into railway tank cars on car floats.

Another object is to eliminate removal of cars from floats during loading, and thereby to effect the loading in a minimum time at a minimum cost with a minimum waste of product. Formerly, where barge movement of railway tank cars has been necessary to reach shipping points it has been necessary to remove the cars from the vessel by motive power. A special floating steel bridge is necessary to convey the cars from barge to shore. A yard and track layout must be provided to convey the cars to the storage tanks and they must there be switched in place at stationary loading racks to receive the fluid. Another switching movement, effected by the locomotive and yard crew returns the car to the barge.

This invention therefore eliminates excessive cost of bridge construction; expense of switching movements; depreciation of equipment; need of transfer yard, tracks and services of engine and train crew.

In actual practice where gasoline storage tanks were a mile from shore, one car has been loaded by this rack in thirty minutes. Without it two hours would be consumed. Use of pressure flow instead of gravity decreases loading time. Ten men are required without the rack; three with it. Ten cars can be loaded in one hour with it; in four hours without it.

When not in use the rack does not interfere with the use of the float for general transportation purposes.

A further object of the invention is to facilitate shipments from water-front industries not reached by rail.

I attain my object by a mechanism which comprises a series of pipes or conduits into which the fluid is conducted from an ex-

terior source of supply. The apparatus consists of a main feed line which may be placed longitudinally in the center of a car float. The main line is provided with a flange-fitted opening and a gate-valve through which the fluid may pass. In the main line, on each side of the point where the fluid enters, is a gate-valve to control the flow in either direction. This feed line may be horizontal, or the intake portion may be lower than its ends to facilitate drainage when not in use. A series of upright pipes or risers connect with it at intervals and extend vertically upward. To the upper end of each riser a movable flexible pipe-arm, or conduit is connected and extends laterally so that its free end may reach the dome of a tank car adjacently placed for loading. These lateral branches may be of any desired length. If rigid they may be constructed to pivot on the joint connection with the riser and the end may be fitted with an L-union, nipple or nozzle to direct the fluid downward into the car. Such a pipe-arm may have one or more sections connected with each other by flexible joints. If the lateral branches are of flexible hose the free end may have a suitable fitting attached, through which the fluid may be discharged into the car dome. These upright standpipes or risers may be supported and connected by a frame-work of wood, steel or other rigid material. This frame may support a platform connecting the risers. To the platform at each side of each riser footways may be connected by hinge-joints so that any one of them may be raised or lowered to connect with the top of the car and facilitate handling the lateral pipe-arms. Near the upper end of each riser is a gate-valve to control the flow of liquid. To each end of the main feed line is connected a pipe leading to a source of compressed air which may be contained in a series of air pressure tanks joined together by a pipe line fitted with valves to control the flow of air. By the introduction of air into the feed line after loading has ceased, the apparatus may be cleared of fluid.

This mechanism is illustrated by the accompanying drawings in which Figure I is a plan view, Figure II is a side longitudinal elevation and Figure III is a cross section at the intake valve near the center

of the main feed line, but showing also the air intake valve at either end of the air line.

A more detailed description of my apparatus is as follows:

From the flexible hose, pipe or conduit 18 connecting with the source of fluid supply, the fluid is conducted by means of a gate-valve 1 into the main feed pipe 4 through which the flow is controlled in each direction by gate-valves 2 and 3. From the main feed line, upright pipes or risers 5 are connected by union joints to the main feed line to carry the fluid to the lateral arms 6. Each lateral arm is connected with its riser by a pivotal joint to allow horizontal movement of the arm to either side. The end of each lateral arm is open and is provided with a terminal fitting 9 through which the fluid may be discharged into the dome 7 of a tank car 8. There may be as many risers as desired, according to the length of the car float and its capacity for car placement. The flexible arm at the top of each riser may be of any desired length. It may be of hose or other flexible material, or pipe in one or more sections connected by flexible union joints. Near the upper end of each riser is a gate-valve 10 to control the flow of fluid. By means of these valves the liquid may be cut off from any one or more of the lateral arms without affecting the others.

The main feed line may be located longitudinally along the center of a car float 11 between car tracks over which tank cars may move to suitable loading positions.

The risers may be braced by a frame work 11^a of wood or other rigid material. The frame work may support a platform 12. To the platform at either side of each riser a movable footway 13 may be attached by means of a hinge-joint at one of its ends, which allows it to be raised to a vertical position when not in use or lowered to the car top when in use. The footway may be of such length as to reach the top of a tank car when placed for loading and may be connected with the platform at any point where it will best facilitate the handling of the lateral branch pipe-arms.

To each end of the main feed line a small pipe 14 is joined, from which compressed air may be introduced into the main feed line by means of valves 16 from an air storage supply. The compressed air may be stored in tanks 15 connected by a pipe line. The air line may be fitted with valves 19 at either end, through which the air may be introduced into the air line from exterior

sources. The air line may be fitted with an air gauge 17 at any point thereon to show the air pressure. Through the air line compressed air may be introduced by valves 16 into the feed line to discharge the fluid therefrom after loading has ceased. Ejection of the fluid is controlled by gate-valves 10, 1, 2 and 3.

The air line and feed line may be placed above or below the deck of the car float, but it is preferable to place the liquid feed line above the deck in order to detect leaks.

Although I have described my invention as embodied in a particular form and especially adapted for a certain purpose, namely, the loading of gasoline tank cars on car floats at docks from a shore supply, I do not confine myself to this particular embodiment of the invention nor to any particular use.

Having thus described my invention, I, therefore, claim:

In an improvement in a fluid-loading rack, a combination of a floating barge, and, mounted thereon, a series of pipes to convey fluid, including a main pipe provided with gate-valves to control the flow therein, fastened longitudinally in a horizontal position in the center portion of the barge; and, attached to the main pipe at intervals, a series of branch upright pipes or risers, each provided with a gate-valve near its upper end to control the flow therein, and each having a lateral branch extension open at its end and attached to the top of the riser by a pivotal joint so that it may move horizontally,—each lateral branch pipe having one or more arms connected with each other by flexible joints and each lateral branch having an opening at its end to which is attached a fitting suitable to direct the flow of the fluid into a tank car below; and a supporting frame of rigid material to which the upright pipes are attached and upon which is mounted a platform, to which platform, near each upright pipe, footways connect by hinge-joints to facilitate reaching the cars and handling the movable lateral branch pipes; and also, as part of this combination, a compressed-air storage-and-conveyor pipe line mounted on the floating barge and connected with the main fluid line near each end, the air line being fitted with valves near the points of its connection with the fluid line, to control the outflow of air into the fluid line—the air line also being fitted with valves to control the flow of air into it from exterior sources.

ELMER HAMMOND.
